TRAILER HITCH

Norman C. Brown, 111 Bruning Ave., Rio Vista, Calif. 94571; Charles W. Brown, 1031 Johnfer Way, Sacramento, Calif. 95831; and Norman R. Brown, Orangevale, Calif. (1017 Charleston Circle, Roseville, Calif. 95678)

Filed Apr. 19, 1973, Ser. No. 352,620

Term of patent 14 years

Int. Cl. D12—16

U.S. Cl. D12—162

Fig.-1

Fig.-2

Fig.-3

Fig.-4

FIG. 1 is a top, right, front perspective view of a trailer hitch, showing our new design;

FIG. 2 is a bottom, left, rear perspective view thereof;

FIG. 3 is a front elevational view thereof, with the tongue plate shown in an alternate position; and

FIG. 4 is a right side elevational view of FIG. 3.

We claim:

The ornamental design for a trailer hitch, as shown and described.
